UNITED STATES PATENT OFFICE.

CHARLES P. ABBEY, OF CHICAGO, ILLINOIS, ASSIGNOR TO KARBUB COMPANY, OF CHICAGO, ILLINOIS, A CORPORATION OF ILLINOIS.

CARBURETER.

1,290,028.

Specification of Letters Patent.

Patented Jan. 7, 1919.

Application filed March 27, 1916. Serial No. 86,828.

To all whom it may concern:

Be it known that I, CHARLES P. ABBEY, a citizen of the United States, and a resident of Chicago, in the county of Cook and State of Illinois, have invented a certain new and useful Improvement in Carbureters, of which the following is a specification.

This invention relates to carbureters.

The object of the invention is to provide a carbureter which shall be simple in construction, efficient in operation and inexpensive to manufacture as compared with any carbureter now on the market, of which I have any knowledge.

15 To effect these ends, a carbureter of my invention comprises the various features, combinations of features and details of construction hereinafter described and claimed.

Referring now to the drawings,

20 Figure 1 is a sectional elevation of my improved carbureter on the line 1—1 of Fig. 2,

Fig. 2 is a top plan view thereof showing the carbureter proper in section on the 25 line 2—2 of Fig. 1,

Figs. 3 and 4 are sectional plan views on the lines 3—3 and 4—4, respectively, of Fig. 1,

Fig. 5 is a perspective view of the throttle 30 valve removed from the carbureter casing,

Figs. 6 and 7 are separate perspective views of the different parts of said throttle valves; and

Fig. 8 is a view illustrating a carbureter 35 embodying my invention in slightly modified form.

My improved carbureter comprises a body portion or casing, designated as a whole A, consisting preferably of a hollow cylinder 1, 40 provided with a mixing chamber 2, an air admission passageway 3, and with a discharge opening 4. Said carbureter is adapted to be connected to the manifold of an engine by means of a usual connection 5 secured to the upper end thereof.

55 Rotatably mounted in the carbureter casing and extending both above and below the lower end of the mixing chamber 2, is a throttle valve 6. As shown, the upper end 50 of said throttle valve is rotatably fitted to a bearing formed by the bore of a sleeve 7 which extends into the mixing chamber from a flange 8 which closes the lower end of said mixing chamber, and the lower end of said

throttle valve is rotatably fitted to a bearing 55 formed by the bore of a sleeve 9 which, in turn, is rotatably fitted to a suitable bearing in the lower end wall of the carbureter casing.

Hydrocarbon is adapted to be supplied to 6 the carbureter from a suitable source of supply, as a float reservoir A', through a nozzle 10, which extends into the lower end of the hollow throttle valve 6. My invention 65 contemplates the use of any desired or approved form of float reservoir and nozzle and the same need not therefore, be described in detail.

Preferable, also, a perforated baffle 11 surrounds the discharge opening 4 of the 70 carbureter, which will operate, in an obvious manner, to promote thorough vaporization of the hydrocarbon and a thorough intermixture of the hydrocarbon vapor and air, whereby a highly effective explosive mixture 75 will be produced.

In the preferable construction shown, the sleeve 7 and the baffle 11 form a cylinder, designated as a whole 12, supported within the mixing chamber 2, substantially concentric therewith, the upper end of said cylinder being secured in the discharge opening of the carbureter and its lower end in an opening formed in the flange 8. The ends of said cylinder are open and the interior 80 thereof is divided about midway between its ends, by a transverse partition 13, the portion of said cylinder below said partition forming the sleeve 7 and the portion of said cylinder above said partition being perforated and forming the baffle 11.

In use, the partition 13 will close the upper end of the throttle valve 6 and its lower end is closed by a plug or bushing 15, which is provided with a hole to receive the 95 nozzle 10, said hole and nozzle being substantially concentric with the throttle valve 6 so as not to interfere with rotation thereof.

The quantities of air and of hydrocarbon supplied to the carbureter, both actual and 100 relative, and thus the "richness" of the explosive mixture, is controlled by the throttle valve 6 in the following manner:—Formed in the side walls of said throttle valve and of the rotatable sleeve 9, respectively, are 105 air admission ports 17 and 18 through which the chamber 19 of the carbureter casing 1 below the flange 8 therein will communicate

with the interior of the throttle valve 6 when said valve is turned to bring said ports 17 and 18 into full or partial register with each other. As shown, there are two sets of 5 ports 17 and 18 located at opposite sides of said throttle valve and also on opposite sides of the air admission opening 3 of the carburetor casing 1. In the preferable construction shown, also, the overlapping sides 10 of each set of ports are inclined relative to each other, whereby as said valve is turned to completely close said ports, the final port openings will be triangular in shape, thus providing for a very fine adjustment of said 15 port openings. As shown, the overlapping sides of the ports 17 in the throttle valve 6 are thus inclined or beveled, the relation being such that said ports 17 will flare downwardly. This particular relation may, 20 however, be varied as desired.

Similar ports 20 and 21 are also formed in the upper end of the throttle valve 6 and in the sleeve 7 whereby the interior of the throttle valve 6 may be brought into communication with the mixing chamber 2 by turning said throttle valve to bring said 25 ports 20 and 21 into register with each other.

Rotation is adapted to be imparted to the throttle valve 6 and sleeve 9, independently 30 of each other, by means of suitable connection between lever arms 22 and 23 secured to the ends of said throttle valve 6 and sleeve 9 which project below the end of the valve casing, and usual levers mounted on 35 the steering post, dash, or other part of the car, not shown, where they will be conveniently accessible to the person who is driving the car.

The air and hydrocarbon supplied to the 40 carburetor is controlled primarily by the throttle valve 6, while the adjustable sleeve 9 is designed for varying the extent of opening of the valve ports 17 and 18 as compared with the extent of opening of the valve ports 45 20 and 21, whereby the quantity of air supplied to the carburetor and the operative suction of the engine on the nozzle 10 may be varied to produce desired relative proportions of air and of hydrocarbon to form an 50 explosive mixture of desired richness.

With the described construction, it is obvious that the air and hydrocarbon vapors delivered from the carburetor to the engine will follow a very tortuous path which will 55 result in very effectively vaporizing the hydrocarbon and thoroughly mixing or intermingling the air and hydrocarbon vapor so as to produce a very effective explosive mixture. In the preferable construction shown, 60 also the upper ends of the ports 20 and 21 are located a short distance below the partition 13, whereby the momentum of the hydrocarbon particles drawn through the nozzle 10 by the suction of the engine will 65 cause them to strike the partition 13, thus

operating to break up any particles of liquid hydrocarbon and facilitating vaporization thereof to a material degree.

As shown, the lower end of the carburetor casing forms a hood which incloses the 70 throttle valve 6 and associated parts and the air admission passageway 3 is formed by a tubular extension 24 of the carburetor casing, whereby the carburetor may be inclosed to provide for heating the explosive mixture 75 supplied to the engine, all in a familiar manner.

As the full equivalent of the partition 13, my invention contemplates equally the use of a cylinder 12, which is open from end to 80 end, and closing the upper end of the throttle valve 6. In many applications, also, the perforated baffle 11 may be dispensed with without seriously impairing the efficiency of the carburetor.

This modification is shown in Fig. 8 of the drawings, in which 1' designates the valve casing, 2' the mixing chamber, 7' the sleeve supported within said mixing chamber, said sleeve being open from end to end, 6' the 90 throttle valve, the upper end of which is fitted to the bearing formed by the bore of said sleeve 7', and the upper end of which is closed as shown at 25. The upper end of the throttle valve 6' and the bearing sleeve 95 7' are provided with ports 20' and 21', by means of which the interior of said throttle valve may be brought into communication with the mixing chamber 2' all as in the preferred form of the carburetor.

85

100

I claim:

1. In a carburetor, the combination of a casing provided with a mixing chamber and with a discharge opening therefrom, a hollow throttle valve, sleeves fitted to said 105 throttle valve one of which is positioned within the mixing chamber of said carburetor, and the other outside thereof, a hydrocarbon supply nozzle which extends into said throttle valve, said throttle valve and the sleeves fitted thereto being provided with ports comprising ports adapted for admitting air to the interior of said throttle valve and separate ports for admitting explosive mixture from said throttle valve to the mixing chamber, said ports forming the sole means for admitting air and explosive mixture to said throttle valve and mixing chamber, respectively, substantially as described.

110

115

120

2. In a carburetor, the combination of a casing provided with a mixing chamber and with a discharge opening therefrom, a hollow throttle valve, a hydrocarbon supply nozzle which extends into said throttle valve, a hollow member supported within the mixing chamber, one end of which is secured in the discharge opening of the carburetor and the other in the lower wall of the mixing chamber, the ends of said hollow member 125

130

- being open and a partition which divides said hollow member transversely between its ends, the walls of the section of said hollow member adjacent to the discharge opening of 5 the carbureter being perforated and the portion thereof below said partition forming a sleeve fitted to the upper end of the throttle valve, and a sleeve fitted to said throttle valve outside of said mixing chamber, said 10 throttle valve and sleeves being provided with ports comprising ports adapted for admitting air to the interior of said throttle valve, and separate ports for admitting explosive mixture from said throttle valve to 15 the mixing chamber, substantially as described.
3. In a carbureter, the combination of a casing, a partition which divides said casing into upper and lower compartments, said 20 partition being provided with a hole, the upper of said compartments forming a mixing chamber and being provided with a discharge opening, and the lower of said compartments forming a hood and being provided with an air admission opening, a sleeve 25 which surrounds the hole in said partition and which extends into the mixing chamber, and a rotatable, hollow valve-member supported within the carbureter casing the upper end of which extends into and is fitted to the bore of the sleeve in the mixing chamber, and the lower end of which projects into the hood chamber of the carbureter, a hydrocarbon supply nozzle which extends into the 30 lower end of said hollow valve-member, a sleeve fitted to said hollow valve-member within said hood chamber, the ends of said hollow valve-member being closed in use and said hollow valve-member and the sleeve in the hood chamber of said carbureter casing the upper end of which extends into and is fitted to the bore of the sleeve in the mixing chamber, and the lower end of which 35 extends into the lower end of said hollow valve-member, a sleeve fitted to said hollow valve-member within said hood chamber one thereof being provided with a bearing in the lower end wall of the carbureter casing, the ends of said hollow valve-member being closed in use and said hollow valve-member and the sleeve in the hood chamber of said carbureter casing being provided with a port or ports adapted for admitting air to the interior of said hollow valve-member, and said hollow valve-member and the sleeve in said mixing chamber being provided with a port or ports adapted for admitting explosive mixture from said hollow valve-member to said mixing chamber, substantially as described.
4. In a carbureter, the combination of a casing, a partition which divides said casing into upper and lower compartments, said partition being provided with a hole, the upper of said compartments forming a mixing chamber and being provided with a discharge opening, and the lower of said compartments forming a hood and being provided with an air admission opening, a sleeve which surrounds the hole in said partition and which extends into the mixing 50 chamber, and a rotatable, hollow valve-member supported within the carbureter casing the upper end of which extends into and is fitted to the bore of the sleeve in the mixing chamber, and the lower end of which 55 extends into the hood chamber of the carbureter, a hydrocarbon supply nozzle which extends into the lower end of said hollow valve-member, a sleeve fitted to said hollow valve-member within said hood chamber one thereof being provided with a bearing in the lower end wall of the carbureter casing, the ends of said hollow valve-member being closed in use and said hollow valve-member and the sleeve in the hood chamber of said carbureter casing being provided with a port or ports adapted for admitting air to the interior of said hollow valve-member, and said hollow valve-member and the sleeve in said mixing chamber being provided with a port or ports adapted for admitting explosive mixture from said hollow valve-member to said mixing chamber, substantially as described.
6. In a carbureter, the combination of a casing, a partition which divides said casing into upper and lower compartments, said partition being provided with a hole, the upper of said compartments forming a mixing chamber and being provided with a discharge opening, and the lower of said compartments forming a hood and being provided with an air admission opening, a sleeve which surrounds the hole in said partition and which extends into the mixing chamber, and a rotatable, hollow valve-member supported within the carbureter casing the upper end of which extends into and is fitted to the bore of the sleeve in the mixing chamber, and the lower end of which 60 extends into the hood chamber of the carbureter, a hydrocarbon supply nozzle which extends into the lower end of said hollow valve-member, a sleeve fitted to said hollow valve-member within said hood chamber one thereof being provided with a bearing in the lower end wall of the carbureter casing, the ends of said hollow valve-member being closed in use and said hollow valve-member and the sleeve in the hood chamber of said carbureter casing being provided with a port or ports adapted for admitting air to the interior of said hollow valve-member, and said hollow valve-member and the sleeve in said mixing chamber being provided with a port or ports adapted for admitting explosive mixture from said hollow valve-member to said mixing chamber, substantially as described.

4

to the bore of the sleeve in the mixing chamber, and the lower end of which extends into the hood chamber of the carbureter, a hydro-carbon supply nozzle which extends into 5 the lower end of said hollow valve-member, a sleeve rotatably fitted to said hollow valve-member within said hood chamber one thereof being provided with a bearing in the lower end wall of the carbureter casing, the 10 ends of said hollow valve-member being closed in use and said hollow valve-member and the sleeve in the hood chamber of said carbureter casing being provided with a port or ports adapted for admitting air to 15 the interior of said hollow valve-member, and said hollow valve-member and the sleeve in said mixing chamber being provided with

a port or ports adapted for admitting explosive mixture from said hollow valve-member to said mixing chamber, and means 20 applied to the lower ends of said hollow valve-member and of the sleeve in the hood chamber of the carbureter casing for turning said hollow valve-member and sleeve, substantially as described.

25
In testimony that I claim the foregoing as my invention, I affix my signature in the presence of two subscribing witnesses this 23rd day of March, 1916.

CHARLES P. ABBEY.
